UNITED STATES PATENT OFFICE

108,064

DESIGN FOR A COMBINATION CLEARANCE SIDE MARKER AND CORNER LAMP FOR MOTOR VEHICLES

George F. Burgess, New Orleans, La., assignor
to Automotive Lighting Equipment, Inc., New
Orleans, La., a corporation of Louisiana

Application October 30, 1937, Serial No. 72,538

Term of patent 7 years

To all whom it may concern:

Be it known that I, George F. Burgess, a citizen of the United States, residing at New Orleans, in the Parish of Orleans and State of Louisiana, have invented a new, original, and ornamental Design for a Combination Clearance Side Marker and Corner Lamp for Motor Vehicles, of which the following is a specification, reference being had to the accompanying drawing, forming part thereof.

Figure 1 is a view in top plan of a combination clearance side marker and corner lamp for motor vehicles embodying my new design;

Figure 2 is a view in front elevation;
Figure 3 is a view in elevation of the inner side
of the lamp;

Figure 4 is an elevational view of the outer
side of the lamp.

I claim:

The ornamental design for a combination
clearance side marker and corner lamp for
motor vehicles, as shown.

GEORGE F. BURGESS.
